UNITED STATES PATENT OFFICE.

GEORGE A. BURNHAM, OF SAUGUS, MASSACHUSETTS, ASSIGNEE TO SEARS R. CONDIT, JR., OF BROOKLINE, MASSACHUSETTS.

REVERSE-CURRENT RESPONSIVE DEVICE.

Application filed March 17, 1916, Serial No. 388,178.

To all whom it may concern:

Be it known that I, GEORGE A. BURNHAM, a citizen of the United States, residing at Saugus, in the county of Essex and State 5 of Massachusetts, have invented an Improvement in Reverse-Current Responsive Devices, of which the following is a specification.

My invention relates to apparatus or devices adapted to control the opening of an electric circuit upon the reversal of current flow therein or when such reversed current flow exceeds a predetermined amount.

Reverse current responsive devices or 10 reverse current relays are commonly constructed having a current coil energized by the current flow in the circuit to be controlled and a potential coil energized by the potential of said circuit. The flux resulting from said potential and current coils is commonly arranged to oppose each other upon reverse current conditions and the resultant flux acts upon a common core or armature which is attracted by the united 15 flux of said coils to open the circuit controlled by the device.

Such a device, while operating satisfactorily to cause the opening of the circuit upon a reversal of current flow therein, is 20 also operable to cause the opening of said circuit upon a straight overload of sufficiently high value. Such an action of a reverse current device is not usually a desirable feature. Furthermore, the operation 25 of the device depends to a large extent upon the value of the potential. The lower the potential, the higher must be the value of the reversed current to cause the operation of the device to interrupt the circuit in 30 which the reversed current flow takes place. This also is an undesirable feature inasmuch as there are conditions in the circuit to cause a reversed current flow therein which operate to reduce to a very low value the 35 potential across the potential coil and thereby cause the device to be inoperative or unresponsive to any reversed current except that of an extremely high value.

An object of my invention is the provision of a device which will operate to interrupt a circuit upon a reversal of current flow therein and which will be solely responsive to a reversal of current flow therein and will be inoperatively affected by a 40 straight overload in the circuit.

A further object of my invention is the provision of such a device in which a decrease of potential operates to cause its operation at a relatively lower value of reversed current rather than to increase, in effect, the reversed current value at which the device is caused to operate upon a reversal of current flow in the circuit.

A further object of my invention is to provide a device whose tripping power, that is, ability of the device to trip a breaker or open a circuit, is independent of the value of the current or potential at which it is caused to operate.

Briefly my invention consists in a current coil and a potential coil arranged normally to oppose each other in a common magnetic circuit and act in conjunction to hold an armature in attracted position also arranged, upon reverse current conditions, to act in conjunction in the common magnetic circuit thereby to release the armature which will move, under spring or other influence, to govern the circuit to be protected.

Fig. 1 is a side elevation of the reverse current device embodying my invention associated with a circuit breaker and operable to open said breaker upon a reversed current flow.

Fig. 2 is a front elevation of the reverse current device embodying my invention.

Fig. 3 is a detail of the movable member of the device and means for adjusting the tripping current value thereof.

Fig. 4 is a detail of the device and circuit breaker in an operated condition of the device.

Fig. 5 is a plan view of the relay with the current and potential coils removed and showing the magnetic circuit.

As here shown, the device includes the potential or shunt coil 10 and the current or series coil 11 arranged respectively upon the potential core 12 and current core 13 comprising a part of a closed rectangular magnetic circuit which is completed by the cross bars 14 and 15, in the extremities of which said cores are secured. Said bar 15 has a recess 16 at about its central portion and a strip 17 of non-magnetic material is arranged therein. Said strip extends above said bar 15 and is provided with reflexed portions 18 between which is pivoted an armature 19 which extends over said other cross bar 14. Said armature 19, in a bridg-

ing position across both bars 15 and 14, divides the rectangular magnetic circuit into two halves, one of which includes the flux from the potential or shunt coil and the other of which includes the flux from the current or series coil.

Said armature 19 is provided with a knob 20 at its extremity by means of which it may be reset manually after an operation.

16 A link 21 is pivoted near the end of said armature at 22 and is operatively connected by means of the pin 23 operating in the slot 24 at the end of said link with the latch 25 of a current breaker or other circuit controlling device having a movable or brush member 26.

In an inoperative position of the device, the armature 19 is maintained by the energization of said potential or shunt and current or series coils adjacent said cross bars 14 and 15. Upon a reversal of current flow, said armature is released and caused positively to be moved upward thereby to cause the tripping of said latch 25 and the opening of the breaker and the interruption of the circuit controlled thereby.

Said slot 24 at the end of said lever 21 forms means whereby the armature 19 of the reverse current device may be reset without moving said latch 25 into such a position that the breaker cannot be closed after being opened by the device.

Said strip 17 is provided with reflexed portions 18^a extended below said cross bar 15 and a forked lever having arms 27 and 27^a is pivoted thereto. Said forked lever provides means whereby the reverse current device may be conditioned for operation upon differing values of reversed current flow.

45 A block 28 having a central opening therein is pivoted at 29 between the arms of said forked lever. A rod 30 has one end slidably arranged in the central opening of said block 28 and its other end is disposed in a recess 31 in the under side of said armature 19 and is forcibly held in said recess by a spring 32 which engages said block 28 and a collar 33 fixed to said rod 30. By such an arrangement said armature 19 is normally pressed upward toward an operated position, being restrained from upward movement, however, by the normal energization of the current and potential coils.

55 By the provision of the sliding and pivotal connection between said rod 30 and the forked lever, such an upward movement of the armature 19 is permitted without causing the disengagement of said rod from said forked lever and armature.

Said forked lever is movable about its pivot point toward or away from said armature 19 thereby to increase or decrease the compression of said tripping spring 32 and cause said armature to move upward upon

a lower or higher value respectively of reversed current flow.

A strip 35 has its ends secured respectively to said strip 17 and said bar 14 and is provided with an arcuate portion 36 corresponding to the path of movement of the end of said lever 27 and is positioned adjacent the end of said lever. Its outer face may be provided with a series of calibrations at which the forked lever may be set 75 for various conditions of operation. A slot 37 is formed in said arcuate portion 36 and a button 39 is screw threaded on said bolt 38 and forms means whereby said lever may be secured in any adjusted position to the 80 arcuate portion of said strip 35. Said button, for the purpose of moving said lever from one position to another position, will be slightly unscrewed, thereby to free said lever from said strip 35 and afterward 85 tightened to clamp said lever to said strip. A pointer 40 is arranged on said bolt 39 and is adapted to register with a calibration on said strip 35 to indicate the setting of the device.

90 When the reverse current device above described is in use to protect a circuit against reversal of current flow therein, the potential coil is connected across or in shunt with the circuit to be protected, and the current or series coil 11 is connected in series with the circuit to be protected. The connections of the coils with the circuit are so arranged that when current is flowing in the proper direction in the circuit, the flux in the rectangular magnetic circuit due to the potential coil is normally bucking the flux in said magnetic circuit due to the series coil. Opposite consequent poles are thereby set up in the two cross bars 14 and 15 adjacent the 105 ends of the armature 19 and said armature is pulled down to its normal attracted position, or it may be manually moved into such position, where it will be held by the flux of both the potential and series coils against 110 the action of the spring 32. Said potential and series coils therefore normally act in conjunction, or assist each other, through the armature 19, while normally bucking each other through the rectangular magnetic 115 circuit. When the current in the circuit including the series coil 11 becomes relatively reversed, the instantaneous polarity of said coil becomes reversed with respect to the instantaneous polarity of the potential coil 120 and consequently the consequent poles normally set up in the cross bars 14 and 15 disappear and the flux due to the two coils assists each other in rectangular magnetic circuit and consequently, as there is no flux, 125 or at the most, unsufficient flux, to hold the armature 19 in attracted position, the spring 32 acts to force the armature 19 upward into retracted position. As said armature moves upward, the link 21 connected therewith is 130

also moved upward and the pin 23 carried by the latch 25 of the circuit breaker is moved to rotate the handle 25^a of the switch in the direction indicated by the arrow, Fig. 4, to open the circuit.

The device will operate to control the circuit upon relative reversal of current flow and without regard to the value of the reversed current flow; and it operates to control the circuit during the period of current reversal. At the instant of reversal of current flow, the flux due to the current coil is substantially nil so that, at that instant, the flux due to the potential coil is substantially the only flux passing through the rectangular magnetic circuit and acting upon the armature 19. The flux from the potential coil may flow through that portion of the magnetic circuit on which the current coil is wound and it may also flow through the armature 19 as both are magnetically in parallel.

Due to the division of the total flux of the potential coil, that portion passing through the armature 19 is insufficient to retain said armature in attracted position against the spring 32 and consequently said spring operates to move said armature 19 upward to retracted position thereby to open the circuit, and this action may occur before sufficient time has lapsed to cause the building up of reverse current of substantial magnitude and at least the value of the reverse current does not control the opening of the circuit.

The device may also operate as an under-current relay to open the circuit when the current in the circuit and in the series coil 11 drops to a predetermined low value and the operation under such conditions is substantially the same as above set forth.

The device may operate upon reversal of current flow and without regard to the value of the potential of the circuit. If the potential becomes reduced as, for instance, due to a short circuit on the circuit near the device, the flux due to the potential coil becomes decreased and the attractive effect on the armature 19 becomes reduced, and consequently the spring 32 is the more effective in moving the armature 19 to retracted position to open the circuit.

Because the series and potential coils normally assist each other, or act in conjunction on the armature, regardless of the strength of current flow in the potential coil, the armature will be held down and consequently the device will not operate upon a straight overload, regardless of its value.

Upon a reversal of current flow, the flux distribution in the magnetic circuit is such that the armature will be moved up with considerable force to cause the opening of the circuit breaker. In order to prevent the

armature from again being attracted upon a high value of reverse current flow, the cross section of the series core 13 is made smaller than the cross section of the potential core 12 whereby said core 13 becomes 70 saturated before a high value of reversed current flow is reached and consequently an increase of reverse current flow has but a small effect upon the armature 19 and consequently is not effective in causing the 75 armature to be sealed in attracted position or to be moved into attracted position after it has moved a slight distance upward toward open position by the reversal of current flow, upon the instant of such reversal.

While the device is here shown as associated with a circuit breaker and is operable to cause the opening of said circuit breaker upon a reversal of current flow, yet 85 instead of the armature being connected with the latch of the circuit breaker, it may be otherwise connected or arranged to control a circuit.

It is to be noted that this device operates 90 upon the instant of reversal of current flow and not, as in previous devices, when the reversed current flow has attained some predetermined value.

I claim:

1. A reverse current protective device comprising a series coil, a potential coil, a common magnetic circuit for said coils, an armature associated with said magnetic circuit arranged normally to be held in attracted position and to be released to move to a retracted position upon relatively reversed current conditions in said coils. 95

2. A reverse current protective device comprising a series coil, a potential coil, a common magnetic circuit for said coils, an armature associated with said magnetic circuit, said coils arranged normally to act in opposition through said magnetic circuit and in conjunction through said armature 100 whereby to hold said armature in attracted position and upon relatively reversed current conditions to act in conjunction through said magnetic circuit and in opposition through said armature whereby to release 105 said armature to permit it to move to an operated position.

3. A reverse current protective device comprising a series coil, a potential coil, a common magnetic circuit therefor and an 110 armature associated with said magnetic circuit arranged normally to be held in attracted position and to be released upon relatively reversed current conditions in said 115 coils and means forcibly to move said released armature to an operated position. 120

4. A reverse current protective device comprising a series coil, a potential coil, a common magnetic circuit therefor, and a 125 spring-pressed armature associated with said 130

- magnetic circuit, said coils arranged normally to hold said armature in attracted position and upon relatively reversed current conditions to release said armature to permit it forcibly to move to an operated position.
5. A reverse current responsive device having a series coil, a potential coil, a common magnetic circuit therefor, an armature arranged to be operably affected upon relatively reversed current conditions in said coils, said magnetic circuit having a portion thereof of reduced cross-section whereby to restrict the magnetizing effect of said current coil on the magnetic circuit.
6. A reverse series device comprising a current coil, a potential coil, a common magnetic circuit therefor, and an armature associated with said magnetic circuit, said coils arranged normally to hold said armature in attracted position and upon relatively reversed current conditions therein to weaken their attractive effect upon the armature to permit said armature to move away from attracted position.
7. A reverse current protective device comprising a rectangular structure adapted to provide a magnetic circuit, series and potential coils disposed on opposite legs of said structure, the leg associated with said series coil arranged to become saturated for values of current flow in said coil above a predetermined value, while the remainder of the magnetic circuit is below saturation, whereby to restrict the effect of said series coil, and an armature associated with said magnetic circuit arranged to be operably affected by relatively reversed current conditions in said coils.
40. 8. A reverse current protective device for electric circuits comprising a series coil, a potential coil, a common magnetic circuit for said coils, an armature associated with said magnetic circuit, said coils arranged to act in opposition through said magnetic circuit and in conjunction through and attract said armature upon normal current conditions in said coils and to act in conjunction through said magnetic circuit and release said armature upon a relative reversal of current flow in said coils, and means forcibly to move said armature to retracted position upon such reversal of current flow in said coils.
55. 9. A reverse current responsive device comprising a series coil, a potential coil, a common magnetic circuit for said coils, said potential and current coils arranged to normally act in opposition through said magnetic circuit, an armature movable to a bridging position across said magnetic circuit between said coils and normally held in such position by the flux in said circuit, and means to move said armature to a remote position upon a relative reversal of current flow in said coils.
10. A reverse current responsive device comprising a series coil, a potential coil, a common magnetic circuit therefor having means to restrict the effect of said series coil on said circuit, said coils arranged to act in opposition through said magnetic circuit under normal current conditions therein, an armature associated with said magnetic circuit and arranged to bridge said magnetic circuit between said coils and to be normally attracted to and held in bridging position by the flux in said magnetic circuit under normal conditions of circuit flow in said coils and to move into retracted position upon a relative reversal of current flow in said coils.
11. A reverse current responsive device comprising a series coil, a potential coil, a common magnetic circuit therefor having means to restrict the effect of said series coil on said circuit, said coils arranged to act in opposition through said magnetic circuit under normal current conditions therein, an armature associated with said magnetic circuit and arranged to bridge said magnetic circuit between said coils, and to be attracted to and held in bridging position by the flux in said magnetic circuit under normal conditions of current flow in said coils, and a spring positively to move said armature into retracted position upon a relative reversal of current flow in said coils.
12. A reverse current responsive device comprising a series coil, a potential coil, a common magnetic circuit therefor, an armature associated with said magnetic circuit arranged to provide an independent magnetic circuit for each coil and be held in attracted position upon normal conditions of current flow in said coils, said magnetic circuit having means to restrict the effect of said series coil on said armature upon a current flow in said coil in excess of a predetermined magnitude, and means to move said armature to a retracted position upon a relative reversal of current flow in said coils.
13. A reverse current responsive device comprising a series coil, a potential coil, a magnetic circuit for said coils, an armature included in said magnetic circuit, arranged normally to be held in attracted position upon normal current flow conditions in said coils, and means to move said armature into a retracted position upon a relative reversal of current flow in said coils, said means acting with a force independent of the value of the reversed current flow.
14. A reverse current responsive device comprising a rectangular structure adapted to provide a magnetic circuit, series and potential coils associated on opposite legs of said structure, the leg of said structure associated with said series coil having insufficient

magnetic material and adapted to become saturated for values of current flow in said coil above a predetermined magnitude, a pivoted armature arranged to be moved to and be held in an attracted position across said structure between said coils upon normal conditions of current flow in said coils, and a spring to force said armature to a retracted position upon a relative reversal of current flow in said coils.

15. In a reverse current responsive device comprising a rectangular structure adapted to provide a magnetic circuit, series and potential coils arranged on opposite legs 15 of said structure, the leg of said structure associated with said series coil having insufficient magnetic material and adapted to be-

come saturated for values of current flow in said coil above a predetermined magnitude, a pivoted armature arranged to be moved to and be held in an attracted position across said structure between said coils upon normal conditions of current flow in said coils, a spring to force said armature into a retracted position upon a relative reversal of current flow in said coils, and means to adjust the tension of said spring.

In testimony whereof, I have signed my name to this specification, in the presence of two subscribing witnesses.
